CLAIM

The ornamental design for tea kettle handle and spout cover, as shown and described.

DESCRIPTION

FIG. 1 is a front perspective view of tea kettle handle and spout cover, showing my new design;

FIG. 2 is a front elevational view thereof;

FIG. 3 is a rear elevational view thereof;

FIG. 4 is a side elevational view thereof, the opposite side of which is an identical mirror image;

FIG. 5 is a top plan view thereof; and,

FIG. 6 is a bottom plan view thereof.

The dotted lines shown in the drawings are environmental only and form no part of the claimed design.
